UNITED STATES PATENT OFFICE.

CLARK T. BUSH, OF ONEONTA, NEW YORK.

IMPROVEMENT IN IRON FENCE-GATES.

Specification forming part of Letters Patent No. **138,071**, dated April 22, 1873; application filed December 6, 1872.

To all whom it may concern:

Be it known that I, CLARK T. BUSH, of Oneonta, in the county of Otsego and State of New York, have invented certain Improvements in Iron Gates, of which the following is a specification:

My invention consists in the various improved devices described herein.

Referring to the drawing accompanying this specification: The main frame of the gate consists of a single bar of iron, H, bent so as to form the three sides of a parallelogram, and having an eye turned on each end of the bar for a hinge. The frame is braced by the rod B, the lower end of which has an eye turned to fit upon the lower gate-hinge. The upper and forward end is shaped so as to fit on the lower side of the rod H, and is adjustably se-

cured thereto by the band n. By means of the brace-rod B and band n the gate may be adjusted to the grade upon which the fence is built. The pickets P P are secured to the upper and lower sides of the frame, and the latch is attached to the front side thereof.

What I claim as my invention is—

The gate consisting of the single bar H, pickets P P, and adjustable brace-rod B provided with an eye to fit upon the lower gate-hinge, and secured at the upper end by the adjusting-band n, substantially as described and shown.

CLARK T. BUSH.
